FIG. 24

UNITED STATES PATENT OFFICE

LOUIS H. GEBHART, OF DAYTON, OHIO, ASSIGNOR TO THE GEBHART FOLDING BOX COMPANY, OF DAYTON, OHIO, A CORPORATION OF OHIO

BOX MAKING MACHINE

Application filed March 10, 1930. Serial No. 434,563.

This invention relates to a machine and method of manufacturing collapsible folding boxes.

It is the object of my invention to manufacture at very high speed a complete box ready for folding and use from a continuous strip of material so that many thousands of boxes can be made and put out without being touched by hand and without individual insertion of the material in the machine.

It is an object to provide in such machine serrated edges to provide serrated slots and to score the box for folding, all at one continuous operation.

It is a further object to provide means for stripping the box and the scraps from the box-forming rolls, to separate the completed box from the strip of stock and to chop the waste stock into small pieces for ready removal from the machine.

It is a further object to provide a machine which can be adjusted for various types of boxes without interfering with the set-up of the machine.

It is an additional object to provide a machine which is adjustable to different types of boxes and different forms thereof.

Referring to the drawings:

Figure 1 is a side elevation of the complete machine;

Figure 2 is a top plan view of the machine; Figure 3 is a section on the line 3-3 of Figure 2, showing diagrammatically the progress of the stock strip through the machine;

Figure 4 is a detailed side elevation, partially in section showing the details of the gearing and adjusting mechanism for the several rolls and feeders in the machine;

Figure 5 is a front elevation partially in section of one corner of the machine showing the same mechanism as in Figure 4, looking at Figure 4 from the right hand side;

Figure 6 is a detailed side elevation of the upper and lower rolls showing one end thereof as both ends are identical;

Figure 7 shows one form of the box at one end thereof as produced by this machine;

Figure 8 shows one end of a box as pro-

duced by the particular serrating knives and cutters shown in Figure 6;

Figure 9 is a section on the line 9-9 of Figure 2 through the upper roll showing the right hand side thereof carrying the gears;

Figure 10 is a similar view showing the lower right hand side thereof;

Figure 11 is a section through the rolls on the line 11-11 of Figure 2;

Figure 12 is a section on the line 12-12 of Figure 2 showing the box stripper;

Figure 13 is a plan view of the box stripper;

Figure 14 is a section through the rolls on the line 14-14 of Figure 2 showing the scrap stripper;

Figure 15 is a top plan view of the top of the scrap stripper;

Figure 16 is a perspective of the serrating knives;

Figure 17 is a detail plan view of the box die for the corner lock;

Figure 18 is a side elevation thereof;

Figure 19 is a top plan view of the corner cutter;

Figure 20 is a side elevation thereof;

Figure 21 is a section on the line 21-21 of Figure 6;

Figure 22 is a section on the line 22-22 of Figure 2;

Figure 23 is a section on the line 9-9 of Figure 2 through the upper roll, showing the left-hand end thereof;

Figure 24 is a similar view showing the left lower roll.

Referring to the drawings in detail, it will be understood that in the operation of the machine the material out of which the boxes are made is a relatively pliable stock and is supplied on a large roll designated 1 from which is taken off a strip of material 2 that is fed between the guide rollers 3 mounted on the frame 4. The strip passes over the tension roller 5 and the tension strip 6 mounted on the bracket 7 and thence passes over the guide roller 8 carried in the bracket 9 between a pair of guiding tension rollers 10. It thence passes beneath the punch or cutting roller 11 and over the die roller 12 to a point between the feed rollers 13 and 14. Hence it

85

90

95

100

passes between the guide plates 15 and 16 and is engaged by the rubber surface rollers 17 and 18 which are turning at a higher speed than the previous rollers thereby serving to pull the complete box strip 19 along the line where it has already been serrated or cut as at 20 causing it to part from the main strip 2. Thence it is guided downwardly by the cam shaped feeder members 21 over the articulate guide plate 22 on the endless belt 23 that is simultaneously driven with the remainder of the mechanism from a common source of power.

The primary objective of my invention is to provide an automatically operated, very high speed machine producing thousands of boxes from a continuously moving strip of stock. This makes it possible to meet competitive conditions in the box industry and it completely eliminates all labor except a single unskilled supervisory operator who may attend a group of machines embodying my invention.

Box forming rolls

The box forming rolls 11 and 12 are respectively formed with serrating, cutting or scoring means projecting from the upper roll and adapted to extend in the corresponding depressions in the lower roll.

Referring to Figures 9 and 10 in particular, it will be observed that the upper roll is so constructed that it may be of any desired width with any combination of cutting, scoring or serrating members all of which can be locked in position without disturbing the rest of the machine thus making my machine adaptable to a wide variety of box constructions.

It will be observed that an upper stationary axle 25 is connected to a lower stationary axle 26. This connection by means of a bolt 27 is carried by the blocks 28 and 29 on the respective axles, which are spaced by the spacer sleeves 30 on the bolt 27. Lubricant is diverted from the lubricant cup 31 through the lubricant passageway 32 and passageway 33 to the surface of the bearing sleeve 34 which supports on the axle the roll 11 and its associate mechanism. A similar cup and grooves are provided in combination with a lower axle.

Mounted upon the bearing sleeves at either end of the axles 25 and 26 is the main roll sleeve, the ends of which engage the shoulders 35 of the bearing sleeves. One of these bearing sleeves engages at one end on each axle a permanent shoulder 36 and 37 respectively. The ends of the bearing sleeves respectively engage detachable collars 37a and 38 which are keyed by the keys 39 and 40 to the stationary axle. Suitable locking collars are threaded upon the two axles as at 41, 42, 43 and 44 in order to hold these collars in position.

Mounted upon the roll sleeves 11 and 12 are a series of separable sleeves and a series of scoring, serrating or cutting knives that are spaced laterally in order to provide the desired construction of boxes from the strip 70 that is passing between the rolls.

The roll sleeve 11 has on either side of the center thereof sleeve portions 45. On one side of this sleeve portion 45 is a shoulder 46 having a groove 47 in which the box stripper finger operates. (See Figures 12 and 13.) A scoring ring 48 is mounted on the drum, then a ring 49 with a stripping groove 50 thereafter and a serrating ring 51 having teeth 52. (See Figure 16.) Additional rings 80 may be provided as at 53 including a locking ring 54 which is threaded upon the drum 11.

Mounted upon a shoulder of the drum 11 is a shoulder ring 55 having a shoulder 56.

Associated with the ring 53 is a scrap stripping surface 57. On the end of the roll is the gear 58 held in place by the retaining sleeve 59 and the bolts 60.

On the other end of the roll on the other side of the annular portion 45 similar members are located and identified by similar numerals.

Referring to the roll or drum 12, it is provided with a plurality of spacer sleeves 61 abutting the central annular shoulder 62. The sleeves 63 are provided with scoring grooves 64 and knife grooves 65. The lower gear 66 is held in position by a gear 67 and bolt 68.

The other end of the roll is provided with the threaded locking ring 69 for similar purposes. A spacer roll 70 is provided with a locking ring 71 retained by the bolt 72.

The arrangement of the serrating knives, stripper grooves, etc., for producing a box, such as is shown in Figure 8 is well shown in Figure 6. The serrated knife 73 cuts the box off along the edge 20, thus dividing the box from the blank after it has been formed. The angular serrated knife 74 makes the serrated slits for locking purposes designated 75. The straight score is made by the knife 76 as at 77. The sides 78 of the box are formed by the annular knife 51 having teeth 52. The scores for the box are made by the scoring rings such as 48 and the transverse scores are made by the transverse score blades 48a.

These transverse score blades and serrated knives are locked into position after having been dropped in the appropriate slots located transversely of the converging sleeves or rings mounted upon the drum that is supported on the axle. They are locked into position by the taper head screws 79 as indicated in large detail in Figure 21 and also as shown in Figure 11.

In order to assist in stripping the stock from the rolls, spring-pressed plungers 80 are mounted in the face of the rolls and are actu- 130

ated by the springs 81. The plungers are retained in position by the blocks 82.

Referring to Figures 17 and 18, it will be noticed that the angular scoring and cutting for the corner lock is effected by the female members 83 having the V-shaped slots 84. These members are carried by the typical ring 85 which can be mounted on the drum 12 and receive in these slots the knives 74 and 76.

Figures 19 and 20 show the male knife member 86 that cuts the angular edge 78a connected on ring 86a.

Stripper mechanism

Referring to Figures 12 and 13, it will be noted that the strip of stock 2 due to the high speed of the rolls has a tendency to follow around the rolls. Stripper fingers 87 which are inserted in the grooves heretofore mentioned serve to lift the stock off of the rolls. These stripper fingers are provided with horizontal supporting plates 88 attached thereto by the screws 89. These plates are carried on bolt 90 supported by the frame 91. In order to strip the sheet of refuse stock that remains after forming the box, stripper fingers 92 are provided having a tapered face 93 terminating in a sharp edge 94. These fingers are likewise supported by the bolts 90 on the bar 91.

Rejector roll mechanism and adjustment therefor

In order to provide the proper elevation for the rejector roll mechanism so that it shall be in alignment with the space between the rolls as the rolls are changed from time to time for varying types of boxes there is provided on the machine bed 92a a vertically disposed frame 93a on either side of the machine. This frame supports a second frame 94a which is slidably mounted thereon on the guideway 95. A hand wheel 96 operates a shaft 97 which carries a gear meshing with the gear 98 which is mounted upon the screw bolt 99 so that as the gear 98 is operated it will serve to elevate the frame 94a in which it is mounted. This results in elevating the frame 94a and its associated mechanism such as the rolls 13 and 14. The rolls 13 and 14 are carried on an upward projection 100 on the frame 94a. This projection also supports on the brackets 101 the bar 101a which carries the guide plates 16. The rolls 13 and 14 are provided with gears 102 and 103 which intermesh. The gear 103 is driven by the gear 104 which in turn meshes with the gear 66 on the roll 12 carried by the axle 26. This axle also carries the gear 67 which in turn is operated by the gear 106. Gear 106 meshes with gear 107 and gear 108. Gear 108 is mounted on the shaft 109 having a beveled pinion 110 meshing with the beveled pinion 111 that drives the shaft 112. This shaft is

carried in the bracket 113 that is mounted on the bed 92a.

In order to accommodate the vertical adjustments of the frame 94a the shaft 112 is provided with a bearing 113a that forms a jaw to carry the gear 114, which is splined in the keyway 115 on the shaft 112. This gear is operated by a gear 116a within the housing 116 of the transverse shaft 117. This shaft likewise carries a keyway 118 to accommodate horizontal movement of the sliding carriage 119 to which it is attached by the bearing 120. Thus the shaft 117 is adapted to move vertically without demeshing the connecting gears.

The shaft 117 carries a bevel pinion 121 that meshes with the bevel pinion 122 on the shaft 123 of the ejector roll 18. The frame 119 also carries the shaft 124 of the ejector roll 17. By moving the frame 119 fore-and-aft of the machine, different lengths of boxes can be accommodated. The hand wheel 125 is for this purpose. It operates the shaft 126, the bevel pinion 127, the bevel pinion 128 and the shaft 129 which is threaded within the block 130 on the end of the frame 94a.

The shaft of the ejector 21, of which there are a plurality across the machine, is designated 131. This shaft is provided with a gear 132 that is supported in the yoke 133 in connection with the shaft 131. This yoke has a pair of sleeve arms 134 through which passes the shaft 117a. Between these arms and carried on the shaft 117a is the gear 135 driving the gear 132 on the shaft 131. The shafts 117a and 117 are connected by a universal joint 136. The shaft 131 is swung on the arms 137 upon the shaft 124. It is raised and lowered about the shaft 124 by the links 138 having eyes 139 supporting the shaft 131. These links are threaded at 140 and, therefore, travel within the bearing 141 which embraces the gear 142 that is driven by a gear 143, mounted on the hand wheel shaft 144. 145 is a sleeve bearing on shaft 144. This shaft is operated by the hand wheel 146.

The endless belt 23 is suitably driven by gear 146a, worm 147, shaft 148, bevel pinion 149 and power pinion 150 connected to the remainder of the machine. 151 is a flywheel 115 of the machine.

Waste cutters

The shaft 152 which supports the roll 13 carries drums 153 with a plurality of transverse serrating knives 154 which successively, intermittently engage the surface of the strips of surplus stock cut from the boxes and chop these strips into pieces between the knives 154 and the rolls 14.

Suitable guide fingers 155 are employed at intervals to guide the completed box into position for storage or stacking.

It will be understood that I desire to comprehend within my invention such modifica-

tions as may be clearly embraced within the scope of my claims and invention.

Having thus fully described my invention, what I claim as new and desire to secure by Letters Patent, is:

- 5 1. In a box-forming machine, means for supplying continuous strip of box stock, means for forming between rolls through which said stock passes box blanks and partially converting them from the strip of stock, tensioning means on either side of said rolls, the blank-forming means acting to maintain the stock at a predetermined tension, means for pulling the box sections at a faster rate than the movement of the strip of stock to complete the detachment of such sections and stripper means for stripping said stock and box blanks from said rolls.
- 10 2. In a box-forming machine, means for supplying a continuous strip of box stock, means for forming between rolls through which said stock passes box blanks and partially converting them from the strip of stock, tensioning means on either side of said rolls, the blank-forming means acting to maintain the stock at a predetermined tension, means for pulling the blank sections at a faster rate than the movement of the strip of stock to complete the detachment of such sections and stripper means for stripping said stock and box blanks from said rolls, said stripper means comprising box blanks stripper means and waste stock stripper means.
- 15 3. In a box-forming machine, means for supplying a continuous strip of box stock, means for forming between rolls through which said stock passes box blanks and partially converting them from the strip of stock, tensioning means on either side of said rolls, the box-forming means acting to maintain the stock at a predetermined tension, means for pulling the box sections at a faster rate than the movement of the strip of stock to complete the detachment of such sections, stripper means for stripping said stock and box blanks from said rolls, said stripper means comprising box blank stripper means and waste stock stripper means and means for converting said waste stock into lengths as it is ejected from the machine.
- 20 4. In combination, in a box-making machine, means to supply a continuous strip of stock, resistance means for resisting the movement of said strip, means to pull said strip against said resistance, punch and die means for forming box blanks from said strip and partially converting them, means for actuating said forming means to also feed said strip and blanks, and means driven simultaneously therewith at a higher rate of speed for engagement of the box blanks only to pull them from the main strip of stock.
- 25 5. In combination, in a box-making machine, means to supply a continuous strip of stock, resistance means for resisting the movement of said strip, means to pull said strip against said resistance, punch and die means for forming box blanks from said strip and partially converting them, means for actuating said forming means to also feed said strip and blanks, and means driven simultaneously therewith at a higher rate of speed for engagement of the box blanks only to pull them from the main strip of stock.

movement of said strip, means to pull said stock against said resistance, punch and die means for forming box blanks from said strip and partially converting them, means for actuating said forming means to also feed said strip and blanks, means driven simultaneously therewith at a higher rate of speed for engagement of the box blanks only to pull them from the main strip of stock and means simultaneously driven with said pulling means for removing the surplus stock after the formation of the box blanks.

6. In combination, a box-making machine, means for forming box blanks and partially converting them from a strip of stock, means to pull said strip of stock and blanks between said blank-forming means, additional pulling means traveling at a greater rate of speed for detaching said box blank from the strip of stock and adjusting means for adjusting the elevation of said pulling means.

7. In combination, a box-making machine, means for forming box blanks and partially converting them from a strip of stock, means to pull said strip of stock and blanks between said blank-forming means, additional pulling means traveling at a greater rate of speed for detaching said box blank from the strip of stock, adjusting means for adjusting the elevation of said pulling means and for adjusting the elevation of said higher speed converting means.

8. In combination, a box-making machine, means for forming box blanks and partially converting them from a strip of stock, means to pull said strip of stock and blank between said blank forming means, additional pulling means traveling at a greater rate of speed for detaching said box blank from the strip of stock, adjusting means for adjusting the elevation of said pulling means and for adjusting the elevation of said higher speed converting means, and means for adjusting the longitudinal position between said means to accommodate different lengths of box blanks.

9. In a box-making machine, superimposed pulling rolls for a continuous strip of stock, a frame therefor, means to adjust said frame vertically, a second pulling means driven at a higher rate of speed than the first-mentioned pulling means comprising rolls adapted to detach formed blanks partially converted from the strip of stock and means to change the longitudinal distance between said pulling means to accommodate different lengths of box blanks.

10. In a box-making machine, superimposed pulling rolls for a continuous strip of stock, a frame therefor, means to adjust said frame vertically, a second pulling means driven at a higher rate of speed than the first-mentioned pulling means comprising rolls adapted to detach formed blanks partially converted from the strip of stock, means to change the longitudinal distance between

said pulling means to accommodate different lengths of box blanks and intermittently ejecting means simultaneously driven with said pulling means and adjustable longitudinally with the second pulling means.

11. In combination, in a box-forming machine, a source of power, box blank forming rolls driven thereby, pulling rolls driven thereby, higher speed blank detaching rolls driven thereby, ejector cams driven thereby.

12. In combination, in a box-forming machine, a source of power, box blank-forming rolls driven thereby, pulling rolls driven thereby, higher speed blank detaching rolls

15 driven thereby, ejector cams driven thereby, an adjustable frame for carrying said pulling rolls, high speed ejecting rolls, and ejector cams, and means for adjusting vertically said frame with respect to the blank-forming 20 rolls.

13. In combination, a machine bed, a guide frame and a vertically movable frame guided thereby, means to adjust the vertical position of said vertically movable frame, a horizontally 25 slidable frame on the vertically movable frame, and means to adjust the position of said last-mentioned frame on the vertically movable frame.

14. In combination, a machine bed, a guide 30 frame and a vertically movable frame guided thereby, means to adjust the vertical position of said vertically movable frame, a horizontally slidable frame on the vertically movable frame, means to adjust the position of said 35 last-mentioned frame on the vertically movable frame, rolls carried by said last-named frame and means for driving said rolls arranged for continuous operation irrespective of the adjustment vertically and horizontally 40 of said frames.

15. In combination, a machine bed, a guide frame and a vertically movable frame guided thereby, means to adjust the vertical position of said vertically movable frame, a horizontally 45 slidable frame on the vertically movable frame, means to adjust the position of said last-mentioned frame on the vertically movable frame, rolls carried by said last-named frame, means for driving said rolls arranged for continuous operation irrespective of the adjustment vertically and horizontally 50 of said frames and a swinging frame and cams with a cam shaft connected to said driving means and mounted on the horizontally 55 slidable frames.

16. In combination, a machine bed, a guide frame and a vertically movable frame guided thereby, means to adjust the vertical position of said vertically movable frame, a horizontally 60 slidable frame on the vertically movable frame, means to adjust the position of said last-mentioned frame on the vertically movable frame, rolls carried by said last-named frame, means for driving said rolls arranged for continuous operation irrespective 65

of the adjustment vertically and horizontally of said frames, a swinging frame and cams with a cam shaft connected to said driving means and mounted on the horizontally slidable frame and a universal joint in said driving means for accommodating said swinging adjustment.

17. In a box-forming machine, a common source of power, punch and die rolls driven thereby, pulling rolls driven thereby vertically adjustable, box blank detaching rolls driven thereby vertically and longitudinally adjustable and ejector cams driven thereby horizontally and vertically adjustable.

18. In a box-forming machine, a common source of power, punch and die rolls driven thereby, pulling rolls driven thereby vertically adjustable, box blank detaching rolls driven thereby vertically and longitudinally adjustable, ejector cams driven thereby horizontally and vertically adjustable and guide plate associated with the pulling rolls and simultaneously vertically adjustable therewith.

19. In a box-making machine, spaced stationary axles gear drums rotatably mounted thereon, bearings at either end of said axles supporting said drums and detachable annular spacer means and box-forming means mounted on said drums.

20. In a box-making machine, spaced stationary axles gear drums rotatably mounted thereon, bearings at either end of said axles supporting said drums and detachable annular spacer means and box-forming means mounted on said drums, said drums having shoulder portions to form abutments for said last-mentioned means to lock them in position.

21. In a box-forming machine, spaced stationary axles, gear drums rotatably mounted thereon, annular serration knives mounted on one of said drums, groove forming means for receiving said knives mounted on the other of said drums, scoring means mounted on one of said drums and scoring-receiving means mounted on the other of said drums.

22. In combination, stationary axles, rotatable drums thereon, complementary serrating means comprising an annular knife and annular means having a knife receiving groove.

23. In combination, stationary axles, rotatable drums thereon, complementary serrating means comprising an annular knife and annular member having a knife receiving groove, annular scorer means comprising an annular scorer mounted on one drum and a scorer receiving sleeve mounted on the other drum.

24. In a box-forming machine, stationary axle, rotatable drums, spacing and locking sleeves mounted thereon and annular and transverse box-forming means locked therein and therebetween.

25. In a box-forming machine, stationary

axle, rotatable drums, spacing and locking sleeves mounted thereon and annular and transverse box-forming means locked therein and therebetween, a portion of said means comprising serrated knife and a portion comprising a scoring means.

26. In a box-forming machine, stationary axle, rotatable drums, spacing and locking sleeves mounted thereon and annular and transverse box-forming means locked therein and therebetween, a portion of said means comprising serrated knife and a portion comprising a scoring means, grooves formed in the surface of said box-forming means and fingers inserted in said grooves for detaching box blank material therefrom as formed into box blanks thereon.

27. In combination, a vertically disposed stripper finger having an arcuate face for engaging a drum and a taper for engaging a strip of material, a horizontal plate attached thereto and means on said plate for attaching it to a support to support it and the finger, whereby said finger may be detached without disturbing said plate and its supports.

28. In combination, in a box-forming machine, feeding rolls, forming rolls, pulling rolls, blank detaching rolls having yielding engaging means on the surface thereof.

29. In combination, in a box-forming machine, feeding rolls, forming rolls, pulling rolls, blank detaching rolls having yielding engaging means on the surface thereof and cam-shaped box blank feeding members.

30. In combination, in a box-forming machine, feeding rolls, forming rolls, pulling rolls, blank detaching rolls having yielding engaging means on the surface thereof, cam-shaped box blank feeding members, an endless conveyor for said box blanks and means for synchronously driving of the forming rolls, pulling rolls, blank-detaching rolls, cams and conveyor.

31. In a box-making machine, the combination of a superimposed stationary axle, drums geared thereon and rotatable on said axles, said drums having central extended shoulders, a plurality of spacer rings on either side thereof forming a roll surface having stripper grooves, annular serrating knives locked therebetween, annular scoring members locked therebetween, transverse scoring knives locked thereon, transverse scoring member locked therein, said lower roll having groove means for accommodating said knives and scoring means as the stock passes between said rolls.

In testimony whereof, I affix my signature.
LOUIS H. GEBHART.
